UNITED STATES PATENT OFFICE.

JOSEPH W. HIGGINS, OF BORDENTOWN, NEW JERSEY.

AUTOMOBILE-HEADLIGHT.

1,244,734.

Specification of Letters Patent. Patented Oct. 30, 1917.

Application filed January 25, 1917. Serial No. 144,419.

To all whom it may concern:

Be it known that I, JOSEPH W. HIGGINS, a citizen of the United States, residing at Bordentown, in the county of Burlington and State of New Jersey, have invented certain new and useful Improvements in Automobile-Headlights; and I do declare the following to be a full, clear, and exact description of the invention, such as will enable others skilled in the art to which it appertains to make and use the same.

This invention relates to improvements in headlights for automobile and other vehicles, the principal object being to provide means whereby the rays of light from the lamp will be diffused and directed downwardly so that the drivers of approaching vehicles and pedestrians will not be blinded by the glare of the lamps.

20 An additional object of the invention is to provide a pane for a headlight through which a maximum amount of light will be directed without any of the glare incident to such lamps.

25 With these and other objects in view the invention resides in the novel features of construction and arrangement of parts which will be hereinafter more particularly described and claimed and shown in the drawings wherein:

Figure 1 is a vertical longitudinal section on the plane of the line 1—1 of Fig. 2;

Fig. 2 is a front elevation of a headlight provided with a pane constructed in accordance with my invention;

Fig. 3 is a detail sectional view through the plate or pane before the same is fully completed; and

Fig. 4 is a fragmentary vertical section 40 showing a slightly modified form of my invention.

Referring to the figures of the accompanying drawing wherein similar reference characters indicate like parts, it will be seen 45 that the numeral 1 indicates a lamp casing of any ordinary or preferred construction provided with the usual source of light, in this case being an electric lamp bulb 2, a deflector 3 for projecting the rays of light 50 from the lamp 2 forwardly through the plate or pane 4 covering the opening in the front of the casing. The invention consists in the novel construction of this pane, 4, the means for holding the same within the

front of the casing depending upon the type 55 of lamp with which it is used.

In most lamps of this nature the pane in the front thereof is circular and of a thickness depending upon its diameter. Therefore I preferably construct my invention 60 so that it may be used in place of any ordinary pane. It is of a thickness somewhat greater than the usual pane and is provided with a plurality of openings 5 extending transversely through the same from its 65 front to its rear face. These openings may be of any desired number or size and arranged in any suitable configuration.

In the present instance the pane is in the form of a flat plate formed of translucent 70 glass or other vitreous material. By thus providing a translucent plate the rays of light will be thoroughly broken up and diffused so that there will be practically no glare. In order to further overcome the 75 usual glare the openings are inclined forwardly and downwardly as clearly shown in Figs. 2 and 3. The rays of light are thereby directed downwardly so that they will strike the ground several yards in front of 80 the automobile. In order that no horizontal rays will be projected from the lamp, the upper edge of the outer end of each of the openings is below the horizontal plane occupied by the lower edge of the rear end 85 thereof.

In the preferred form of the invention illustrated in Figs. 1 to 3, these openings are filled with a transparent glass or other 90 vitreous material 6, thus preventing the entrance of dust or dirt within the casing of the lamp, and also keeping the light therein from being blown out in case it is an acetylene or oil flame. The same result may be also accomplished as shown in Fig. 4. That 95 is to say, a thin plate of transparent glass may be placed in front of the translucent plate containing the openings. In this view, the last mentioned plate is designated by the numeral 4', while the numeral 6' indicates the additional transparent glass plate.

The pane as shown in Figs. 1 and 2 may be constructed in any convenient or desired manner, but the same is preferably first formed from a single piece of transparent 100 glass in which the openings 5 are provided as in Fig. 3, which is a partially completed pane. The openings may then be filled by

pouring in a transparent glass in molten condition. This completes the pane, and when the same has cooled, the material placed in the openings will be formed practically integrally with the other portion.

It is very obvious that a covering for the front of a headlight when constructed as above set forth will be greatly superior to any similar covering already in use. Furthermore its simple construction enables it to be constructed at a slight cost.

I claim:

1. In a lamp, a translucent plate having a plurality of transverse inclined openings extending entirely through the plate from its inner to its outer face.

2. In a lamp of the class described, a translucent plate formed of vitreous material covering the front thereof, said plate having a plurality of forwardly and downwardly inclined openings to permit the rays of light to be projected from the lamp in a downward direction.

3. In a lamp of the class described, a translucent plate formed of vitreous material covering the front thereof, said plate having a plurality of forwardly and down-

wardly inclined openings, the upper edge of the outer end of each of said openings being below the horizontal plane of the lower edge of the inner end thereof, whereby to prevent any horizontal rays of light from being projected from said openings.

4. In a lamp of the class described, a translucent plate formed of vitreous material covering the front thereof, said plate having a plurality of forwardly and downwardly inclined openings, said openings being filled with transparent vitreous material to permit the rays of light to be projected from the lamp in a downward direction.

5. In a lamp, a translucent plate provided with a plurality of transverse inclined openings extending entirely through the plate from its inner to its outer edge, and transparent means for closing said openings.

In testimony whereof I have hereunto set my hand in the presence of two subscribing witnesses.

JOSEPH W. HIGGINS.
